UNITED STATES PATENT OFFICE.

GROVER G. TUTTLE, OF PHILLIPSBURG, NEW JERSEY, ASSIGNOR TO INGERSOLL-RAND COMPANY, OF JERSEY CITY, NEW JERSEY, A CORPORATION OF NEW JERSEY.

WATER-TUBE CONNECTION.

Application filed September 11, 1925. Serial No. 55,682.

To all whom it may concern:

Be it known that I, GROVER G. TUTTLE, a citizen of the United States, and a resident of Phillipsburg, county of Warren, and 5 State of New Jersey, have invented a certain Water-Tube Connection, of which the following is a specification accompanied by drawings.

This invention relates to rock drills, but 10 more particularly to a water tube connection for fluid actuated rock drills of the hammer type.

In rock drills employing tubes for conveying cleansing liquid to the drill hole, 15 considerable difficulty is at times experienced in maintaining fluid tight joints between the tubes and the adjacent parts. Usually, such tubes are clamped firmly to their seat when the drill is assembled, but 20 owing to the extreme vibration set up when the drill is in operation, the clamping means readily become loosened and a portion of the cleansing agent finds its way into the percussive element of the drill and washes 25 away the lubricant. Unless such leakage is early discovered and the proper adjustments made, excessive wear on the movable parts of the drill will take place and thus reduce the efficiency of the drill.

30 It is an object of this invention to prevent leakage of cleansing fluid, such as water, into the percussive element and other movable parts of a rock drill, by means of spring devices for automatically compensating for 35 wear between the tubes and their seats.

Other objects will be in part obvious and in part pointed out hereinafter.

The invention consists of the combinations 40 of elements, features of construction and arrangement of parts substantially as hereinafter described and more particularly pointed out in the appended claims and illustrated in the accompanying drawing, in which

45 Figure 1 is a view in elevation, partly in section, of so much of a rock drill as will serve to illustrate the invention, and

50 Figure 2 is a detail view in section of a back head equipped with a water tube connection constructed in accordance with the practice of the invention.

55 Referring to the drawings, in which one modification of the invention is embodied in a stoper type rock drill, a cylinder A supports at its front end a front head B

into which is inserted a drill steel C. The cylinder A is provided with a reciprocating hammer piston D and an anvil block E is interposed between the piston D and the drill steel C to transmit the blows of said piston to the drill steel. A ratchet ring F is seated in the rearward end of the cylinder A to cooperate with suitable ratchet devices G carried by a rifle bar H engaging the piston D in the usual manner for the purpose of imparting rotary movement to the drill steel C.

In order to advance a drill of the type illustrated in the drawing to the work, a feeding cylinder J is provided preferably coaxially with the cylinder A and has a piston K against which pressure fluid may act for raising or advancing the drill. A back head L is in this instance interposed between the ratchet ring F and the cylinder J and serves to centralize said ratchet ring and the feeding cylinder J. Any suitable means may be provided for holding the parts forming the drill casing in operative position, but such means preferably consist of suitable side bolts (not shown) engaging various lugged portions of the front head B, the cylinder A and the feeding cylinder J, preferably exterior of the drill.

Pressure fluid for actuating the percussive and feeding elements is controlled by a throttle valve O in the back head L and the distribution of pressure fluid to the percussive cylinder A may be controlled by a suitable distribution valve (not shown) operative in a valve chest P. A throttle lever Q secured to the throttle valve O serves as a convenient means for manipulating said throttle valve.

In accordance with the practice of the invention, a pair of tubes R and S extend through the cylinder A and are preferably arranged concentrically with respect to each other. The tube R in this instance serves to convey pressure fluid through the drill and has a flange T at one end to seat on a shoulder U which forms the bottom for a recess V in the back head L. The tube S extends through the tube R and through the anvil block E preferably to a point near the forward end of said anvil block and is of somewhat smaller cross sectional area than the bore of the tube R so that a passage W exists therebetween for con-

veying pressure fluid to the drill steel. Communication is provided between the tube R and the throttle valve O by a port or series of ports X in the wall of the tube 5 R and a passage Y formed in the back head L. A port Z in the throttle valve O is adapted to register with the passage Y when the throttle valve is turned to the position to admit pressure fluid to the per-

10 cussive and feeding elements.

The tube S in this instance is of considerably greater length than the tube R and extends rearwardly through a water plug b to a point near the outer end of said water 15 plug. The water plug b is preferably hollow throughout its length and is screw threaded as at c to engage corresponding screw threads formed in the recess V for holding said water plug in position. By 20 forming tapered threads on the plug b as indicated in the drawing, said plug may be screwed firmly into the back head and thus prevent leakage of water along the threaded portion of the plug.

25 In order to yieldably hold the tube R on its seat, a recessed retainer e is arranged slidably in the water plug b and is pressed firmly against the flange T by a spring f arranged between the retainer e and a shoulder g of a water tube guide h. The water tube guide h, like the retainer e, is also slid- 30 able in the water plug b and has a reduced forward extension j which extends into the interior of the retainer e and cooperates therewith to form a fluid tight joint. The water tube guide h in this instance provides a seat k for a bulb o carried by the tube S. In order to hold the bulb o of the tube S firmly upon the seat k, a plunger p bearing 35 against the bulb o is arranged slidably in the water tube guide h and is actuated by a spring q whereby the bulb o is held against removal from the seat k.

Suitable means are provided for varying 40 the tension of the springs f and q. To this end the outer end of the plug b is provided with internal screw threads r to receive a retaining plug s which also engages the end of the tube S.

45 Cleansing fluid, such as water, is conveyed to the recess V through a connection t and a passage u from whence it flows through a longitudinal external groove v in the water plug b into a water plug cap w and 50 through a restricted port x in the retaining plug s into the tube S. The cap w is in this

instance screwed on the end of the water plug b to prevent leakage of water from the recess V.

The advantages of the invention reside in the fact that any wear which may take place on the bulb o and the flange T and their seats may be automatically compensated for by the action of the springs f and q. By this form of construction, the springs f and q may be placed under a strong tension at the time the water tube parts are assembled and due to the automatic take-up herein provided, further attention on the part of the operator will be unnecessary. This feature is particularly advantageous in drills where ready access to the tube may not be had as for instance the type of drill illustrated in the drawings.

75 I claim:

1. In a fluid actuated rock drill, the combination of a cylinder with a back head, a recess in said back head, a tubular water plug in said recess, an air tube supported in the back head, a flange on said air tube to seat on the bottom of the recess, a water tube arranged concentrically in the air tube and extending through the water plug, said water tube having a bulb near one end, a spring pressed retainer slidable on the water tube for holding the air tube on its seat, a recessed water tube guide slidable in the water plug, and a spring in the water tube guide for holding the bulb yieldably against said guide.

2. In a fluid actuated rock drill, the combination of a cylinder with a back head, a recess in said back head, a tubular water plug in said recess, an air tube supported by the back head and extending through the cylinder, a flange on said tube to seat on the bottom of the recess, a retainer having a spring for holding the flange in fluid tight contact with its seat, a water tube arranged concentrically through the air tube and having a bulb near one end, a recessed water tube guide slidable in the water plug and in the retainer to serve as a seat for said bulb and to compress said spring, a plunger in the water tube guide having a spring for holding said bulb in fluid tight contact with its seat, and means adjustable in the water plug for varying the tension of the springs.

100 In testimony whereof I have signed this specification.

105 GROVER G. TUTTLE.
